F. KOBLE.

TURN TABLE.

APPLICATION FILED JULY 28, 1908

Patented Mar. 16, 1909.

UNITED STATES PATENT OFFICE.

FREMONT KOBLER, OF CHIHUAHUA, MEXICO.

TURN-TABLE.

No. 915,360.

Specification of Letters Patent. Patented March 16, 1909.

Application filed July 28, 1908. Serial No. 445,813.

To all whom it may concern:

Be it known that I, FREMONT KOBLER, citizen of Republic of Mexico, residing at Chihuahua, Mexico, have invented certain new and useful Improvements in Turn-Tables, of which the following is a specification.

It is the general practice in making inspections of railroads to make the trip in a motor car and when it is required to return said car is usually either bodily lifted by a gang of men and turned upon the track or it is necessary to hunt a Y or like contrivance to admit of turning the inspection motor car. Neither of these methods is desirable, as a gang of men may not be conveniently at hand, and a Y or like contrivance may be distant and thereby consume valuable time.

The present invention has for its object to supply a contrivance which may be conveniently and effectually manipulated by one person and carried upon the inspection car in a compact form and which will admit of the car being turned upon the track at any point and at a moment's notice.

For a full understanding of the invention and the merits thereof and also to acquire a knowledge of the details of construction and the means for effecting the result, reference is to be had to the following description and accompanying drawings.

While the invention may be adapted to different forms and conditions by changes in the structure and minor details without departing from the spirit or essential features thereof, still the preferred embodiment is shown in the accompanying drawings, in which:

Figure 1 is a perspective view of a turn-table embodying the invention. Fig. 2 is a longitudinal section on the line x—x of Fig. 4. Fig. 3 is a transverse section on the line y—y of Fig. 4. Fig. 4 is a top plan view.

Corresponding and like parts are referred to in the following description and indicated in all the views of the drawings by the same reference characters.

The turntable is of such construction as to admit of its parts being readily separated and act in a compact form so as to be conveniently carried upon the inspection car and also to admit of its being handled by one person.

The device comprises a block 1 which is preferably of hard wood and covered on its upper side by means of a plate 2 in which a

vertical opening is centrally formed. A transverse bar 3 is mounted upon the block 1 to turn thereon and is provided with a pin 4 mounted in the opening of the block 1, thereby preventing displacement of the bar 3 when the device is in operation. The pin 4 is pendent from a plate 5 which is secured in any substantial way to a transverse bar 3, either by being bolted or riveted thereto. The transverse bar 3 may be of any substantial construction so as to withstand the weight of the inspection car and is provided at opposite ends with stops 6 to prevent displacement of the rails 7. Longitudinal rails 7 are mounted upon a transverse bar 3 so as to tilt thereon, and these rails are channeled or grooved in their upper sides to receive the flanges of the wheels of the inspection car and thereby prevent lateral displacement thereof. The longitudinal rails 7 are upwardly curved at one end, as indicated at 8, to form stops to prevent the car from running over said rails when passing upon the same. In cross section the rail 7 may be of any form, and said rails may be molded or rolled, or manufactured in any manner. A notch 9 is provided in the lower side of each rail intermediate of its ends and is adapted to receive the transverse bar 3 and thereby prevent longitudinal movement of the rail upon the bar when the parts are assembled.

It is noted that the appliance is composed of parts which are readily separable, thereby admitting of the device being readily handled by one person and conveniently carried upon the inspection car.

When placing the device in position for use, the block 1 is set upon a tie and the transverse bar 3 is placed upon the block 1 with the pin 4 entered in the opening thereof, after which the rails 7 are placed in position, the appliance when set up presenting the appearance substantially as shown in the several views of the drawing. The inspection car to be turned is run upon the rails 7 and is balanced thereon, after which the same is turned by swinging the rails 7 and transverse bar 3 about the pin 4 as an axis. Preliminary to turning the car upon the rails 7, the latter are inclined, as indicated by full lines in Fig. 2, and after the car has been run upon the rails and balanced thereon, said rails are tilted into an approximately horizontal position, as shown by the dotted lines in Fig. 2, and in which position the said rails clear the main rails of the track, thereby admitting

of the rails 7, transverse bar 3 and the car mounted on said rails 7, turning. After the car has been turned and adjusted to the main rails, the device is removed from the track 5 and placed upon the car until again required for use. It is proposed to roughen the bottom of the groove or channel formed in the rail 7 to insure sufficient traction between them and the wheels of the inspection motor 10 car to insure the latter maintaining the rails when the latter are inclined, as indicated in Figs. 1 and 2. This may be accomplished in a variety of ways, such as by adding a strip of wood or like material to the upper 15 side of the rail 7, or by roughening the same.

Having thus described the invention, what is claimed as new is:

1. A turntable for use upon railroads to admit of turning inspection motor cars 20 thereon, said turntable consisting of a support, a transverse bar mounted to turn upon said support, and longitudinal rails mounted to tilt upon the transverse bar and to turn therewith.
- 25 2. A turntable for the purposes specified, the same comprising a support, a transverse bar mounted to turn upon said support, and longitudinal rails removably fitted upon the transverse bar and adapted to tilt thereon and to turn therewith.
- 30 3. A turntable for the purpose specified, the same comprising a support, a transverse bar mounted to turn upon said support, and longitudinal rails removably fitted upon the transverse bar and adapted to tilt thereon 35 and to turn therewith, said longitudinal rails having notches in their lower sides to receive the transverse bar.

4. A turntable for the purposes specified, the same comprising a support, a transverse bar mounted to turn upon said support, and longitudinal rails removably fitted upon the transverse bar and adapted to tilt thereon and to turn therewith, said longitudinal rails having grooves or channels in their upper 45 sides to receive the flanges of the wheels of the car and prevent lateral displacement thereof.

5. A turntable for the purposes specified, the same comprising a support, a transverse bar mounted to turn upon said support, and longitudinal rails removably fitted upon the transverse bar and adapted to tilt thereon and to turn therewith, said longitudinal rails having their rear ends upwardly curved to 50 form stops.

6. In a turntable of the character described, the combination of a support, a transverse bar removably mounted upon said support and adapted to turn thereon, 60 and longitudinal rails removably fitted upon the transverse bar and adapted to tilt thereon and to turn therewith.

7. The herein described turntable, comprising a block having a vertical opening, a transverse bar having a pendent pin inserted in the opening of the block, and longitudinal rails mounted upon the transverse bar and having notches in their lower sides.

In testimony whereof I affix my signature 70 in presence of two witnesses.
